Primary Examiner—Bernard Ansher**Assistant Examiner**—Sandra Morris**Attorney, Agent, or Firm**—Norman M. Cameron**[57] CLAIM**

The ornamental design for the crop blower for a combine harvester, as shown.

DESCRIPTION

FIG. 1 is a top, front isometric view of the crop blower for a combine harvester, showing my new design;

FIG. 2 is a front elevation thereof;

FIG. 3 is a rear elevation thereof;

FIG. 4 is a bottom plan thereof;

FIG. 5 is a top plan thereof;

FIG. 6 is an enlarged end elevational view thereof; and,

FIG. 7 is an enlarged right end elevational view thereof.

FIG. 1

FIG. 2

FIG. 3

FIG. 4

FIG. 5

FIG. 6

FIG. 7
